Primary Examiner — Andrew Kerr*Assistant Examiner* — Courtney J Clark-Rasheed*(74) Attorney, Agent, or Firm* — Lowe Graham Jones, PLLC(57) **CLAIM**

I claim the ornamental design for a silicone cup, as shown.

DESCRIPTION

FIG. 1 is a top-right-rear isometric view of a silicone cup, showing my new design.

FIG. 2 is a top-left-rear isometric view of the silicone cup.

FIG. 3 is a top-right-front isometric view of the silicone cup.

FIG. 4 is a bottom isometric view of the silicone cup.

FIG. 5 is a front elevational view of the silicone cup.

FIG. 6 is a left side elevational view of the silicone cup.

FIG. 7 is a right side elevational view of the silicone cup.

FIG. 8 is a rear elevational view of the silicone cup.

FIG. 9 is a bottom plan view of the silicone cup; and,

FIG. 10 is a top plan view of the silicone cup.

1 Claim, 10 Drawing Sheets(56)
